UNITED STATES PATENT OFFICE.

SAMUEL E. TRISLER, OF DAYTON, OHIO.

RADIATOR.

1,013,973.

Specification of Letters Patent.

Patented Jan. 9, 1912.

Application filed February 28, 1910. Serial No. 546,310.

To all whom it may concern:

Be it known that I, SAMUEL E. TRISLER, a citizen of the United States, residing at Dayton, in the county of Montgomery and State of Ohio, have invented certain new and useful Improvements in Radiators, of which the following is a specification.

My invention relates to condensers or fluid cooling apparatus, and more particularly to radiators for cooling the water which has been circulated about the cylinder of an explosive engine, and is especially adapted for use in automobile radiators.

The object of the invention is to greatly simplify the structure as well as the means and mode of operation of such devices, whereby they will not only be cheapened in construction, but will be rendered more efficient and positive in operation, and unlikely to get out of repair.

A further object is to provide an improved form of conduit which will present the maximum amount of surface to the atmosphere, and which will readily permit the expansion and contraction of the conduit, due to varying thermal conditions, without subjecting the conduit to undue strain and the possible rupture of the conduit.

Further objects are to provide an improved form of radiator fin, which will present the maximum amount of cooling surface, and which will interrupt and deflect the currents of air, breaking and dividing the currents in such manner as to secure the greatest efficiency; an additional object is to provide a suitable brace for the conduits which at the same time will give to the structure a pleasing appearance, by forming a front of cellular type, which at the present time is greatly desired in automobile construction.

A further object is to provide means for equal distribution of the water supply to the entire series of conduits.

With the above primary and other incidental objects in view as will more fully appear in the specification, the invention consists of the features of construction, the parts and combinations thereof and the mode of operation, or their equivalents, as hereinafter described and set forth in the claims.

Referring to the drawings, Figure 1 is a front elevation, partly in section of the assembled radiator. Fig. 2 is a detail plan view of several of the conduits removed

from the radiator, showing the relation of the radiating fins and the reinforcing strip. Figs. 3 and 4 are detail views of the conduit formation. Fig. 5 is a detail perspective view of the fin plate after being scored but before being formed. Fig. 6 is a detail perspective view of two of the radiating fins after the forming operation, on an enlarged scale. Fig. 7 is an elevation of the fin plate after the forming operation. Fig. 8 is a detail perspective view of the fins as applied to the tubular conduit forming a part of the present invention. Fig. 9 is a similar view showing the radiator fins applied to a flat conduit similar to those in common use. Fig. 10 is a perspective view of the fin construction wherein the fins are oppositely disposed, for use between closely spaced conduits. Fig. 11 is a perspective view of several conduits with the interposed reinforcing strip whereby the cellular appearance of the front is produced. Fig. 12 is a detail perspective view of the reinforcing strip before being inserted between the conduits. Fig. 13 is a similar view of a modified form of the said strip. Fig. 14 is a perspective view illustrating the cellular front produced by interposing two of the strips as shown in Fig. 13, between the conduits. Fig. 15 is a similar view illustrating the application of the single strip as shown in Fig. 13 to the flat conduits.

Like parts are indicated by similar characters of reference throughout the several views.

In constructing the radiator, there is employed a frame or body having in the upper portion thereof an inlet chamber 1 and in the lower portion an outlet chamber 2. The water or other circulating medium is conducted from the engine or other apparatus to the inlet chamber 1 from which it is conducted to the chamber 2 through a multiplicity of parallel conduits 3. During its passage through the conduits the circulating medium gives off the heat previously acquired, and enters the outlet chamber 2 in a substantially cool condition from which it is returned to the engine or apparatus to again complete the cycle.

Heretofore much difficulty has been experienced through lack of durability of the conduits and the tendency of the conduits to rupture through excessive expansion and contraction due to varying thermal conditions, to which the device is subjected.

The conduits forming a part of the present invention are designed to afford the maximum radiating surface and are to some degree elastic to compensate for expansion and contraction, and the seams are reduced to one per conduit, thus reducing the danger of leaks to minimum.

The conduits 3 each comprise a sheet of metal, corrugated or formed undulating, which is folded upon itself to bring converging undulations into registry, and the opposite edges are united and seamed as at 4. The converging undulations may be united by soldering or "dipping," or the elasticity of the metal may be relied upon, in some grades of material, to hold the converging undulations in contact and thereby divide the conduit into a plurality of separate parallel passages 5 through which the circulating medium is conducted. In several figures of the drawings the inner corrugations have been shown with flat or square faces which join or abut to separate the passages 5. However not all metal will permit the abrupt bending necessary to produce such flat faces, and therefore in some instances the corrugations will be formed with rounded surfaces as in Fig. 4.

The corrugations in the sides of the conduit provide an excess of material to compensate for changes due to thermal variations, and even though through excessive expansion the abutting corrugations separating the passages might be separated no harm would result as it would only permit a small quantity of the circulating fluid to leak from one to another of the passages 5, without escaping from the conduit. The seams 4 of the conduits 3 are not pressed to parallelism with the walls of the conduit, but project beyond the walls and radial thereto, forming extended portions hereinafter referred to.

To facilitate the dispersion of the heat, it is customary to provide fins, points or projections upon the conduits. An improved form of fin is herein provided, which is formed from a flat sheet of metal 7 by scoring or slotting the sheet in rows or series as at 8 Fig. 5, and afterward bending or forcing the strip of material between the slots outward beyond the plane of the plate, thereby forming arches or loops 9 attached at opposite ends to the original portion of the plate. The loops 9 are preferably of angular form and alternately arranged as shown in Figs. 6, 7, 8 and 9 whereby successive loops will be out of registry with each other.

The fin plates are attached to opposite sides of the conduits 3 with the main or original portion of the plate tangential to the corrugations of the conduit walls, leaving openings intermediate the corrugations, and the fins or loops projecting beyond the

plate and forming a crisscross mass as shown in Figs. 1, 8 and 9 through which the air may freely circulate, and wherein the air current will be separated into a multitude of smaller currents which will reach every part of the fin plate and the surface of the conduits. The section 10 of the fin plate between the rows of slots 8, which is the only portion remaining in the original plane of the plate is comparatively small and provides the surface for attachment to the walls of the conduits. By this construction, both surfaces of substantially the entire fin plate are utilized as a cooling surface, in addition to the walls of the conduits intermediate the points of attachment of the plate.

Under ordinary conditions each conduit 3 is provided with two fin plates, one on each side. However in some instances it is desirable to closely space the conduits, in which case, there may not be sufficient space intermediate the conduits to receive two fin plates. To meet such conditions the strips 8 of the fin plate may be alternately pressed in opposite directions as shown in Fig. 10, in which but one fin plate would be used between the conduits, the plate being attached at the apex of the loops to the adjacent conduit walls.

It is desirable to give to automobile radiators a pleasing appearance by providing a cellular front, and also to brace the conduits against undue vibration. This has been attempted by interposing a reinforcing strip between the conduits and rigidly securing such strip to the walls of the conduit. However such construction resisted the expansion and contraction of the conduit and frequently results in rupture of the conduit walls. To obviate this difficulty is one of the objects of extending the seams 4 beyond the conduit walls, as before mentioned.

A reinforcing strip 11 is formed by a plurality of reverse bends in the strip, parts of the structure being reduced to parallelism, thereby forming a perpendicular with a plurality of lateral arms as shown in Fig. 12, which is interposed between the seams and rigidly secured to the extended seams 4 and independent of the conduit walls, whereby it will not interfere with the expansion and contraction of said walls. The reinforcing strip as described and shown in Fig. 12 is formed from a single continuous strip of material; it is obvious however that the reinforcement might be made up of a plurality of pieces variously arranged. In Fig. 14 are shown two strips 12 having a plurality of angular bends therein interposed between the seams of succeeding conduits, forming a multiplicity of angularly arranged cells, while Fig. 15 shows a single strip 12 between the extended seams producing a series of triangular cells.

Figs. 9 and 15 show the fin plates and the reinforcing strips applied to conduits of ordinary construction, except that they have the extended seams 4 before mentioned.

It has been found by experience that in the radiators of usual construction, the centrally located conduits carry the greater portion of the water or other circulating medium, and that frequently the outermost conduits are substantially unused. It is therefore desirable to provide for equal distribution of the water, which is attained by means of the distributing conduit 14 having therein a plurality of discharge orifices so arranged that the discharge will be substantially equal throughout.

The distributing conduit is located within the inlet chamber 1 and communicates with the intake conduit 15. The fluid pressure within the distributing conduit 14 will be greater at points adjacent to the connection with the intake conduit 15, and the tendency would be to force the greater part of the fluid through the adjacent orifices 16, which would over burden the central conduits 3. To compensate for the greater pressure and greater supply at the point of connection of the intake conduit, the discharge orifices 16 are more sparsely located adjacent to the point of connection of the intake conduit, and become more numerous as the distance from said point increases. The same result, it is obvious, might be attained by varying the size of the orifices. The combined capacity of the discharge orifices is proportioned in accordance with the capacity of the intake, making due allowance for the changing of the direction of flow, friction, etc., so that approximately all the openings 40 are utilized and fluid supplied equally to all the conduits 3, which results in more even and thorough cooling of the mass of fluid and greatly increases the capacity of the radiator. In order that the fluid supply 45 may be drawn equally from all parts of the outlet chamber 2, the discharge conduit 17 is similarly provided with intake orifices sparsely located adjacent to the offtake conduit 18 and more numerous as the distance 50 from the offtake connection increases; thus the suction which will be less at the extreme end of the pipe is compensated for by the increased combined area of the intake orifices. The result of this construction is an even distribution of the water which is subdivided into small quantities passing 55 through all of the numerous passages of the conduits 3, which causes the temperature to be lowered very rapidly to a comparative low degree, increasing both the efficiency and capacity of the radiator.

The material employed for the conduits and fin plates may be sheet brass, copper, "gilding" or any other suitable metal or material having heat conductive properties.

While the invention has herein been described in its relation to automobiles, for which it is especially adapted, it is to be understood the invention is not limited to such use, but that the same general construction may be employed for sundry other purposes, for instance in connection with stationary hydrocarbon engines, in connection with refrigerating apparatus for cooling the refrigerating media, or as a heating device by circulating hot water or steam through the device. To these and other uses as will readily occur to any one skilled in the art, the construction may be readily adapted with but few or no modifications; I do not therefore limit the invention to use as an automobile radiator.

From the above description it will be apparent that there is thus produced a device of the character described, possessing the particular features of advantage before enumerated as desirable, but which obviously is susceptible of modification in its form, proportion, detail construction and arrangement of parts, without departing from the principle involved or sacrificing any of its advantages.

Having thus described my invention, I claim;

1. In a radiator, inlet and outlet chambers, a plurality of conduits connecting the chambers, radiator fins attached to each of the conduits comprising a plurality of arches of heat conductive material arranged in rows, the individual arches of each row being set out of registry with succeeding arches of the same row, each conduit and its attached radiator fins being independent of and separate from every other conduit and the fins thereof.
2. In a radiator, inlet and outlet chambers, independent conduits connecting the chambers, radiator fins carried on the conduits comprising a multiplicity of pieces of heat conductive material attached at opposite ends to the same conduit to form a plurality of arches each of such arches being out of registry with the neighboring arches.
3. In a radiator, inlet and outlet chambers, independent conduits connecting the chambers, radiator fins carried on the conduits comprising plates of heat conductive material extending intermediate successive conduits and parallel therewith, said plates having therein a multiplicity of slots, the strips of material formed intermediate such slots being bent into loops or arches projecting beyond the plane of the plate.
4. In a radiator, inlet and outlet chambers, conduits connecting the chambers, radiator fins located intermediate the conduits and attached thereto, comprising strips of heat conductive material attached to the conduits at regular intervals the portion of strips between the points of attach-

ment being bent into arches of which the wall of the conduit forms the base, the arches of succeeding strips of heat conductive material attached to the same conduit being bent out of registry with those of the preceding strip.

5. In a radiator, inlet and outlet chambers, a plurality of conduits connecting the chambers, radiator fins independently carried by each of the conduits comprising a multiplicity of strips of heat conductive material attached at intervals to the same conduit and forming non-registering arches intermediate the points of attachment, each conduit with its attached fins being independent of every other conduit and fins.

6. In a radiator, inlet and outlet chambers, a plurality of conduits connecting the chambers, radiator fins carried by the conduits, comprising plates of heat conductive material, having a multiplicity of slots therein, said plates being located intermediate and parallel with said conduits, the strips of material formed intermediate the

slots in said plates being bent into the form 25 of arches, succeeding arches being out of registry with each other.

7. In a radiator of the character described, inlet and outlet chambers, a plurality of conduits connecting the chambers, a multiplicity 30 of strips of heat conductive material, arranged in series intermediate the conduits, each series of strips extending in a plane substantially parallel with the adjacent conduits, the individual strips of each series 35 being inclined in relation to the walls of the conduits, successive strips of each series being inclined in opposite directions thereby forming a criss-cross structure intermediate the conduits, through which the air is permitted to circulate.

In testimony whereof, I have hereunto set my hand this 9th day of February A. D. 1910.

SAMUEL E. TRISLER.
